TREATING HYDROCARBON OILS

Claude W. Watson, Port Arthur, Tex., assignor to
 The Texas Company, New York, N. Y., a corporation of Delaware

Application June 22, 1932, Serial No. 618,657

2 Claims. (Cl. 196—96)

This invention relates to the refining of hydrocarbons and more particularly to the refining of distillates obtained by cracking petroleum or other hydrocarbons.

5 The invention broadly contemplates a process of producing a color and gum stable hydrocarbon motor fuel which comprises cracking higher boiling petroleum or other hydrocarbons to form vapors of lower boiling hydrocarbons, subjecting 10 these lower boiling vapors while in the freshly formed or nascent condition to fractionation to obtain a vapor fraction having a definite desired boiling range, then immediately contacting this fraction continuously with a suitable adsorbent 15 catalyst by bringing the vapors into intimate contact and in countercurrent with a moving stream of liquid hydrocarbons, in which such finely divided adsorbent catalyst is suspended.

When hydrocarbon oils are subjected to cracking conditions, the products of the reaction include hydrocarbon compounds of varying degrees of unsaturation. The more unsaturated compounds are unstable in that they tend to combine among themselves to form gums or colored compounds. 25 This formation of new compounds of substantially higher molecular weight from unsaturated compounds of lower molecular weight is termed polymerization. While the products of the cracking operation are in the nascent state, that is, immediately upon or after their formation in the cracking reaction, the highly unsaturated and undesirable compounds may quite readily be removed by contacting them with a suitable catalytic adsorbent which selectively 30 polymerizes these compounds. However, if the products of the cracking reaction are exposed to the atmosphere or are allowed to remain in storage for any length of time before they are contacted with such catalytic adsorbent, the accelerated polymerization may not only remove the undesirable highly unsaturated compounds but may also react with those unsaturated hydrocarbons whose presence in the final product is desirable.

45 Therefore, in order to effect the production of color stable cracked hydrocarbon products, it is desirable that the hydrocarbons be treated while in the nascent state, that is to say, immediately upon their formation by the cracking reaction. Practically, this is effected by carrying out the treating operation in direct conjunction with the cracking process.

This invention is directed in part to the continuous and simultaneous treatment of a specific hydrocarbon fraction which may be produced as

the result of either a liquid or a vapor phase cracking operation. The invention may also be used in conjunction with any of the pyrolytic operations, sometimes termed reformations, which are directed to increasing the anti-detonating qualities of hydrocarbon fractions, such as naphtha, kerosene and the like. The invention also finds application in connection with processes in which gaseous hydrocarbons are submitted to controlled pyrolytic conditions where- 10 by there are produced liquid and gaseous hydrocarbons having unsaturated characteristics.

One of the advantages accruing to the operation of the herein disclosed invention resides in the fact that, by treating the nascent hydrocarbon vapors produced by a pyrolytic cracking process with catalytic adsorbents, the accelerated polymerization which takes place is limited to the undesirable highly unsaturated compounds. In this way, the efficiency of the adsorbent is 20 raised and a greater yield of treated product is obtainable with a unit amount of a catalyst material.

In accordance with the invention, a hydrocarbon material is submitted to a pyrolytic process and the vapor products are partially fractionated to produce a broad fraction having definite boiling limits. The purpose of this partial fractionation is to effect as far as possible the elimination of compounds having a boiling point 25 higher than the end point of the final treated hydrocarbon fractions and return them to the pyrolytic cracking conditions. The partially fractionated vapor is then transported to a fractionating tower which also serves as the treating 30 tower. This tower may be of the conventional type having bell-cap plates or similar liquid contact means which may or may not be altered to permit of their dual function. In this fractionating tower the vapors are contacted with 35 a countercurrently moving suspension of clay in hydrocarbon oil which is introduced at an upper point in the tower and which forms pools on each plate of the fractionating tower. The vapors in their upward passage through the tower contact with the clay by passing through these 40 pools of liquid hydrocarbon and clay suspension and are both treated and fractionated. The treated vapor fraction is drawn off at the top of the tower while the mixture of partly spent or 50 completely spent clay and heavy hydrocarbons is drawn off at the bottom of the tower.

In the operation of the herein disclosed process, it is preferable to use those adsorbent catalysts which have the property of exhibiting their great- 55

est activities in decolorizing oils at elevated temperatures. Preferably the adsorbent decolorizing material may be a clay of the montmorillonite type, which has been subjected to a treatment with acid and which exhibits its greatest efficiency at temperatures in excess of 250° F.

The invention will be fully understood from the following description taken in connection with the accompanying drawings which represent 10 in diagrammatic sectional elevation two modifications of an apparatus which may be employed for carrying out the process. The apparatus illustrated in the drawings is shown and described merely for the purpose of aiding in understanding the process and it is to be understood that any 15 other suitable apparatus may be substituted for that shown.

In Figure 1, the numeral 10 designates a charge pump which connects a source of charging stock, 20 not shown, with reflux exchanger 12 through the line 11. This reflux exchanger is situated in the upper part of a fractionating tower to be hereinafter described, and its outlet communicates through the line 13, controlled by the valve 14, 25 with the coil 15 of the preheater 16. The outlet end of the preheater 16 is connected by the line 17 controlled by the valve 18, to an upper point of the reaction chamber 19. A tar draw-off line 20 is provided in the lower end of the reaction 30 chamber, in which line there is interposed a control valve 21. The uppermost point of the reaction chamber is equipped with a vapor line 22 which connects through the expansion valve 23 with a lower point of the fractionating tower 24, 35 which tower may be of the conventional tray type and which is fitted, at its lowest point, with a draw-off line 27, which communicates with the suction side of the hot oil pump 28. This pump discharges into the charge line 31 fitted with 40 valve 32, which line enters the coil 15 of preheater 16 at a point intermediate its inlet and outlet.

The uppermost point of the fractionating tower 24 is provided with a vapor line 33 which connects this point of the tower with a lower point of the fractionating tower 35. A valve 34 is placed in this line for purposes of control. In an upper part of this fractionating tower there is situated a reflux cooling coil 36 while in a lower 50 part of the structure the steam spray 37 is provided.

The lowest point of the fractionating tower 35 is fitted with a liquid draw-off line 38 controlled by the automatic valve 39. This line discharges 55 into the separatory tank 40. The bottom of this tank discharges into the pump 42 through the line 41 and the pump in turn discharges into the manifold line 43. A plurality of branch lines 44, 46 and 48 controlled respectively by the valves 60 45, 47 and 49 connect the manifold line with various levels of the fractionating tower 35.

An upper point of the separatory tank 40 is provided with a draw-off line 51 controlled by the valve 52 which communicates with the suction 65 side of the pump 53. This pump discharges into a pressure filter 55 of suitable type, through the line 54. In order to permit of the removal of separated material from this filter, a solids discharge line 56 controlled by the valve 57 is provided. 70 The outlet of the filter is connected by means of the line 58 controlled by the valve 59 with the mixing chamber 75. In order to permit of the optional recirculation of some or all of the filtrate from the pressure filter to the outlet of the 75 preheater 16, the line 60 controlled by the valve

61 is used to connect the line 58 with the line 17.

The top of the tower 35 is equipped with a vapor draw-off line 62 which communicates through the valve 63 with the condenser coils 64 of the condenser 65. The discharge side of these coils is 5 connected by the line 66 through the valve 67 with the receiving drum 68. The top of the tank is fitted with a vapor off-take line 69 controlled by the valve 70 which leads to a gas compression plant or suitable storage. 10

The aforementioned mixing chamber 75 is connected with a source 78 of adsorbent catalyst by means of the line 79 and with the receiving drum 68 by means of the line 76 controlled by the valve 77. A line 80 controlled by the valve 81 which 15 is connected to a trap tray located immediately below the reflux coil 36 in fractionating tower 37 leads into the mixing chamber 75. In order to permit of the agitation of the contents of the mixing chamber 75, both the mixing device 93 as well 20 as the gas spray 73 are provided. The latter is connected with the vapor off-take line 69 by means of the line 71 controlled by the valve 72. The bottom of the mixing chamber is fitted with a line 84 which in turn is connected to the inlet 25 side of the pump 85. This pump discharges into an upper point of the fractionating tower 35 through the line 86 controlled by the valve 87.

Figure 2 represents a modification of the apparatus shown in Figure 1. It differs from the 30 described apparatus in that two treating and fractionating towers are used in series instead of a single tower. Reference to the figure and the following description will assist in an understanding of the structure of the apparatus and its 35 operation.

The top of the tower 35 is fitted with the vapor line 62 which connects through the valve 63 with the fractionating tower 64. In an upper point of the structure of the fractionating tower there 40 is incorporated a reflux exchanger 65 while a lower point of the structure is equipped with the steam spray 66. The bottom of the tower is connected by the line 67 controlled by the automatic valve 68, with a circulating pump 69 which discharges through the line 70 into an upper part of the fractionating tower 35. The top of the tower 64 is equipped with a vapor line 72 which discharges through the valve 73 into the coils 74 of the condenser 75. The outlet of the condenser coils communicate with the receiving drum 73 through the line 76 controlled by valve 77. The tank is fitted at an upper point of its structure with a vent line 79 controlled by valve 88. 50

The numeral 86 designates a mixing chamber 55 preferably provided with a conical bottom. This chamber is connected with the receiving drum 78 by means of the line 82 controlled by valve 83 and by means of line 85 with the storage vessel 60 84 which serves as a source of adsorbent catalyst. The line 87 controlled by the valve 88 connects a trap tray located immediately below the reflux coil 65 in the fractionating tower 64 with the mixing chamber 86. In order to permit of the agitation of the contents of the mixing chamber 86, both the mixing device 89 as well as the gas spray 92 are provided. The latter is connected with the vapor offtake line 79 by means of the line 90 controlled by the valve 91. The bottom of the mixing chamber is fitted with a line 95 which in turn is connected to the inlet side of the pump 96. This pump discharges into an upper point of the fractionating tower 64 through the line 97 controlled by the valve 98. The top of the mixing chamber is provided with a line 93 controlled 70 75

by the valve 94 which connects the vapor space of the mixing chamber with the vapor off-take line 79.

In the operation of the process in connection with an apparatus such as that illustrated in Figure 1, a higher boiling hydrocarbon oil is charged by the pump 10 through the coils of the reflux exchanger 12 where the temperature may be raised to a temperature of 250° F. by heat interchange with hot oil vapors. The oil is then circulated through the tubes 15 of the preheater 16 where the oil is raised to a temperature at which substantial cracking takes place. This temperature may, with advantage, be in the neighborhood of 900° F. The heated oil is discharged from the preheater under a pressure of 400 lbs. per sq. in. into the reaction chamber 19 where a large portion of the oil is vaporized. The residual non-vaporized oil settles to the bottom of this chamber and may be drawn off through the line 20 to a suitable storage tank. The vapors in the reaction chamber which may have a temperature of 860° F. under the existing conditions of operation, escape through the vapor line 22 and pass into the fractionating tower 24 which may be maintained under a pressure of approximately 350-400 lbs. per sq. in. In this tower a hydrocarbon fraction of widely varying boiling points may be produced. The primary object of the fractionation is to remove those fractions of heavy hydrocarbons which are not desired in the final treated product and which may with advantage be recirculated to the preheater so that they may again be subjected to conditions favoring pyrolytic decomposition. These heavy hydrocarbons collect as a liquid at the bottom of the tower and can be drawn off through the draw-off line 27 which is in communication with the inlet side of the recirculating pump 28. They are then charged by this pump through line 31 and valve 32 into the tubes of the preheater at a point which is situated intermediate the inlet and outlet of the preheater. Under the existing conditions of operation, the temperature of this oil may be about 790° F.

The hydrocarbon vapors which are formed in the fractionating tower 24 are fractionated by passing upwardly through the tower and in countercurrent to the descending reflux liquid which is formed by the heat interchange between the cold charging oil in the reflux exchanger and the vapors which contact the coils of the exchanger. The broad fraction of hydrocarbon vapors which is drawn off from the top of the tower through the vapor line 33 may have a temperature of 660° F. These vapors are transported through the line 33 through the expansion valve 34 where a reduction in pressure may be brought about. Upon leaving this valve, the vapors enter the fractionating tower 35 at a lower point in its structure.

The fractionating tower 35 serves a dual function in that it not only is used for preparing a vapor fraction having definite boiling point limits but is also used as an apparatus for treating with catalytic adsorbents the hydrocarbons introduced thereto. The catalytic adsorbents are introduced into an upper point of the tower in the form of a suspension which may be prepared by admixing with the finely divided adsorbent a quantity of treated hydrocarbons which may or may not have been prepared by this process or by suspending the adsorbents in an oil having a gravity higher than the treated hydrocarbon

product, which oil may be produced as one of the by-products of the process, and, for example, may be taken off from the trap tray situated immediately below the reflux coils 36. So, for example, adsorbent catalytic material stored in storage chamber 78 may be introduced into the mixing chamber 75 where it is agitated with treated oil from the receiving drum 68, with oil taken off from the trap tray in an upper point of the fractionating tower 35, or with a heavier oil obtained by filtering the residual oil from this tower in the pressure filter 55. The operations incidental to the production of this heavier filtered oil will be described hereinafter.

The formation of the suspension of catalytic adsorbent is advantageously brought about by agitating the mixture by means of an agitating device such as that indicated by the numeral 90 in the drawings.

In certain operations of the process the contents of the mixing chamber may be efficiently agitated by introducing into the bottom of the chamber 75 hydrocarbon gases such as those produced in the process and which are separated from the final treated condensate which accumulates in the receiving drum 68. The gases are bubbled upwardly through the mixture of adsorbent catalyst and oil and are drawn off from the top of the chamber through a line which connects with the vapor line connecting the vapor space of the receiving drum with the gas compression plant or the storage for non-condensable gases.

The suspension of catalytic adsorbent in treated oil is then charged by means of the pump 85 into an upper point of the fractionating tower 35 through the line 86 controlled by the valve 87. The catalytic adsorbent and liquid oil then pass downwardly through the tower whereby the ascending hydrocarbon vapors are brought into intimate contact with the adsorbent.

In the operation of the tower, the temperature is maintained sufficiently high to permit of the vaporization of all those hydrocarbon constituents which are desired in the finished product. Hydrocarbons having higher boiling points are separated and collect at the bottom of the tower in admixture with the partly or completely spent catalytic adsorbent. In order to free this mixture of any low boiling hydrocarbons contained therein, it may be desirable to inject steam into the mixture through the steam spray 37.

The mixture of adsorbent and heavy oil which has been denuded of light hydrocarbons is then drawn off through the line 38 controlled by the automatic valve 39 into the separator chamber 40 where some separation of the adsorbent from the oil may take place. The temperature of this mixture in this operation of the process may be about 580° F. In those operations of the tower where the adsorbent is not completely spent, the slurry of adsorbent and oil collecting at the bottom of the separator chamber 40 may be recirculated through the line 43 and the branch lines 44, 46 and 48 to one or more levels of the fractionating tower. In other operations of this process it may be desirable to draw off some or all of the mixture of residual oil and adsorbent which has been introduced into the separator chamber 40. This may be accomplished by placing this chamber in communication with the suction side of the pump 53, which pump is used for charging the mixture to a pressure filter 55. In the filter, substantial separation of the adsorbent from the residual oil is brought about and the adsorbent

so separated is drawn off through the solids discharge line 56 which is controlled by valve 57. The filtrate or treated oil freed from adsorbent is discharged into the line 58. The line 60 controlled by the valve 61 may be caused to communicate with the discharge line 58 so that if it is found desirable, the separated oil may be recirculated to the outlet of the preheater 16 of the cracking unit into the line 17.

10 The treated vapors which escape from the top of the tower 35 pass through the vapor line 62 and the valve 63 into the coils 64 of the condenser 65 where substantial condensation is brought about. The condensate which may have 15 an end point of about 400° F. is drawn off through the line 66 and valve 67 into the receiving drum 68. If found desirable, the condensation may be carried out under pressure by the proper manipulations of the valves 63 and 67. The line 69 controlled by valve 70 which communicates with the vapor space of the receiving drum 68 may connect this drum with a gas compression plant or a suitable storage for the light hydrocarbons and non-condensable gases which may have been 25 formed in the operation of the process.

In carrying out an operation with the apparatus shown in Figure 2, the heavy hydrocarbon oil may be subjected to pyrolytic reactions under conditions of pressure and temperature similar to those used in the apparatus shown in Figure 1. The nascent hydrocarbon vapors produced by such a cracking are subjected to a fractionation whereby hydrocarbons heavier than those desired in the final treated product, are substantially separated. The separated hydrocarbons may, with advantage, be returned to the preheater outlet for resubjection to pyrolytic conditions. In the operation of this modification of the apparatus, the vapor fraction is subjected to treatment in two fractionating towers connected in series. In the first of these towers designated by numeral 35 in Figure 2, the vapors are passed in countercurrent with partly spent adsorbent catalyst which may consist either of that portion of the catalyst which has already been circulated through the tower 35 and which has accumulated in separatory chamber 40 or it may consist of partly spent adsorbent which has been discharged from the bottom of 50 the second fractionating and treating tower, which is operated in series with tower 35. The second tower which is designated by the numeral 64 serves for the final fractionation and final treatment of the vapors which have been discharged from the tower 35. They are caused to travel countercurrently against a flowing stream of catalytic adsorbent suspended in either a treated hydrocarbon oil produced by this process or a heavier hydrocarbon oil which may be produced as a by-product of the process. The

operations incidental to the production of the final treated condensate are similar to those described in the previous description of the apparatus shown in Figure 1.

Obviously many modifications and variations of the invention, as hereinbefore set forth, may be made without departing from the spirit and scope thereof, and therefore only such limitations should be imposed as are indicated in the appended claims.

I claim:

1. The process of producing a color stable motor fuel from heavy hydrocarbons which comprises cracking a higher boiling hydrocarbon oil to produce vapors of lower boiling hydrocarbons, 15 fractionating these vapors to produce a vapor fraction of a definite boiling range, passing this fraction while in a nascent condition into treating and rectifying apparatus where the vapors are simultaneously rectified and contacted with 20 a countercurrently flowing suspension of a catalytic adsorbent and a treated liquid hydrocarbon, then withdrawing the treated and fractionated hydrocarbon vapors and condensing them to yield a color stable liquid suitable for 25 use as a motor fuel while concurrently and simultaneously withdrawing from the rectifying and treating tower those hydrocarbons which remain unvaporized and which occur together with partly or completely spent catalytic adsorbent 30 as a mixture, and recirculating this mixture to one or more different levels of the fractionating tower.

2. The process of producing a color stable motor fuel from heavy hydrocarbons which comprises cracking a higher boiling hydrocarbon oil to produce vapors of lower boiling hydrocarbons, fractionating these vapors to produce a vapor fraction of a definite boiling range, passing this fraction while in a nascent condition into treating and rectifying apparatus where the vapors are simultaneously rectified and contacted with a countercurrently flowing suspension of a catalytic adsorbent and a treated liquid hydrocarbon, then withdrawing the treated and fractionated hydrocarbon vapors and condensing them to yield a color stable liquid suitable for 35 use as a motor fuel while concurrently and simultaneously withdrawing the unvaporized oil which occurs together with the partly or completely spent adsorbent as a mixture, dividing this mixture into two portions, subjecting one portion to a filtration to effect the substantial separation of the oil and the suspended adsorbent, and returning the separated oil to pyrolytic reactions, recirculating the other portion of the mixture to one or more different levels in the fractionating tower structure.

CLAUDE W. WATSON.
